UNITED STATES PATENT OFFICE.

EDGAR M. HAWKINS, OF ROCHESTER, NEW YORK, ASSIGNOR TO M. D. KNOWLTON COMPANY, OF ROCHESTER, NEW YORK, A CORPORATION OF NEW YORK.

TUBE-MAKING MACHINE.

1,157,220.

Specification of Letters Patent.

Patented Oct. 19, 1915.

Application filed May 19, 1913. Serial No. 788,545.

To all whom it may concern:

Be it known that J. Edgar M. HAWKINS, citizen of the United States, and resident of Rochester, in the county of Monroe and State of New York, have invented certain new and useful Improvements in Tube-Making Machines, of which the following is a specification.

This invention relates to a tube making machine for forming tubes of paper, cardboard, or other material from a pasted sheet, by winding the same about a mandrel until the tube has the desired number of layers or plies securely held together by the adhesive to form a tube having a solid wall of the desired thickness.

One of the principal objects of this invention is to provide in a single machine mechanism for applying paste, glue or other adhesive to a moving sheet or web and mechanism for winding the sheet or web so pasted into the form of a tube having the pasted layers firmly adhering to one another.

Another important object of this invention is to provide a tube-making machine in which the clamping of the forward end of the sheet in place in the mandrel, the starting of the machine, the winding of the sheet about the mandrel, the pasting of the successive layers together, and the withdrawal of the pasting means from the paper of the tube being formed, are all under the control of the operator and follow in predetermined sequence upon the gripping of the forward end of the sheet in the mandrel, as a result of manual action by the operator for starting the machine.

Another important feature of the improved machine is that when the tube is finished the operator may, by a single manual action, throw the calender-roll and the mandrel out of operative relation with each other, swing the shiftable bearing usually employed for supporting one end of the mandrel into position for permitting the removal of the finished tube, and perform various other operations incident to stopping the machine, in predetermined sequence.

Other features of the invention relate to means for pressing the last ply of the tube

being formed firmly into engagement with the ply to which it is to adhere by a wiping action in a direction the reverse of that in which the tube is moving, to means for controlling the action of said pressing means, and to various other features of construction, all of which will be hereinafter described and claimed and are illustrated in the accompanying drawings, in which—

Figure 1 is a front elevation, with parts broken away, of a tube-making machine embodying the invention; Fig. 2 is an enlarged side elevation of the main portion thereof; Fig. 3 is an enlarged longitudinal section of the same, the section being taken in line 3—3, Fig. 1, looking in the direction of the arrows; Fig. 4 is an enlarged front elevation of the same, partly in section and with parts broken away to illustrate the construction; Fig. 5 is a section, taken on the line 5—5 of Fig. 1 still further enlarged and similar to Fig. 3, of the central portion of the mechanism shown in said view, and illustrating more in detail the means for holding the paste-applying devices, including the distributing roll, in and out of action, and for permitting movement thereof; Fig. 6 is a front elevation of the same, and also illustrates a portion of the clutch mechanism controlling the main driver; Figs. 7 and 8 are, respectively, a longitudinal section and a front elevation, on a larger scale, of a portion of the mechanism illustrating the mandrel, its shiftable bearing, and means for closing the bearing upon the mandrel and clamping and releasing the forward end of the sheet to be wound into a tube; and Fig. 9 is an enlarged sectional detail and elevation of a portion of the clutch mechanism controlling the operation of the machine.

Similar reference characters designate like parts in all the figures of the drawings.

In many respects the tube-making machine herein shown, which is of a horizontal type adapted for winding what is known as a "lap-tube," is or may be substantially the same as machines of this general type heretofore used. The main mechanism is, as usual, mounted on a relatively long frame or bed, designated generally by 2, rising from

legs 3, and having suitable standards, such as 4, 5, and 5', for supporting the various operative parts, and various other fixtures which will be referred to hereinafter in detail wherever necessary. The main element of the machine is of course a rotary mandrel around which the web or sheet of card-board, paper or other material is to be wound. One form of mandrel suitable for the purpose is illustrated and is designated generally by M. It may be of any type suitable for the purpose. This mandrel is intended to be rotated by a suitable driving mechanism a sufficient number of times to make a tube having a wall of the desired thickness from a rolled sheet to which a suitable adhesive has been applied to the outer surface of the sheet being wound. In addition to these parts there will also be suitable means for trimming the ends of the finished tube and for cutting the same as desired. Except as hereinafter specified, all of these parts and various other parts be similar to those used in machines as heretofore constructed.

The mandrel, which constitutes one of the principal elements of the machine, is shown as driven from a main driver, such as 2, carrying the usual fast and loose pulleys, 7 and 8, said main driver having therewith a small spur-pinion 9, meshing with a large spur-gear, 10, which is mounted on the same axis as the mandrel itself and serves to impart rotary movement thereto. The sheet carrying said gear and to which the mandrel is connected is mounted in suitable bearings in the standards 4 and 5' rising from the bed 2 of the machine, and is indicated at 11. The gear 10 normally turns loosely on the shaft 11 and is intended to be engaged therewith at the proper time, viz., when it is desired to start the machine, by suitable coupling means, one form of which is shown in the drawings. (See Figs. 1 and 9). Here a friction-clutch is illustrated at 12, this clutch is controlled by a suitable shifting lever, 13, pivoted at 14 near the bed of the machine and having its lower end joined by means of a connecting-rod, 15, to suitable connections from a treadle, such as 16, for operating the shifting lever. This shifting lever is normally in engagement at its upper end with a spring-pressed detent, 17, carried by the clutch member 12, the latter being splined to the shaft 11, as shown at 18, and held against rotation with the spur-gear 10 by reason of the engagement of the spring-pressed detent 17 with the upper end of the shifting or releasing lever 13. On depressing the treadle 16 the upper end of the shifting lever is intended to be moved to the left in Fig. 1 to release the detent 17, and permit the clutch 12 and the shaft 11 to be rotated by the spur-gear 10 by frictional engagement of said gear-wheel and clutch.

The web or card-board, paper, or other material to be wrapped around the mandrel, is placed in roll, on a suitable table, such as 21, from which it is fed into the machine over, roller, 19, and under a guide plate, 20, which at this time will be in the elevated position shown by dotted lines in Fig. 3. The free end of the sheet is intended to be supported by a suitable calendar-roll, such as 21, and the mandrel, and guided between these two cylindrical members into position to be engaged by suitable clamping means carried by the mandrel. The clamping means preferred employed consists of a fixed element 22 on the mandrel and 70 a movable section or clamp proper, these fixed and movable elements being indicated respectively by 22 and 23. In the preferred construction the movable member, or clamp proper, is a section of the circumference of 80 the mandrel and is mounted on the mandrel to swing about a pivot, 24, on one edge of the circumference, the amount of this swinging motion being limited from a clamping position in which it constitutes a section of the 90 circumference of the mandrel. The open position of this clamping device is illustrated in dotted lines in Fig. 2 and the closed or clamping position in full lines in the same figure. The forward end of an oncoming 95 sheet is intended to be engaged between the fixed and movable elements of the clamp at a point close to the pivot of the movable element 23, as will be best by referring to Figs. 2 and 3.

Hand-like means are employed for opening and closing at the proper times the clamping device just described. The preferred means employed for operating the movable or swinging clamping section 23 are in the 100 manner, illustrated and related with the main driver 2, 105. The preferred construction is such that when the main actuating device or device for swinging the clamp 23 is, or are, meshed with the mandrel, the means employed comprising two such coaxial elements, one of which is a rod, 25, journaled in a bushing, 26, clamped in place in the mandrel, as by means of a split collar, 27, while the other is a tubular member or 110 sleeve, such as 28, surrounding the rod 25 and its bushing 26, and connected with the rod in such a manner as to have a relative turning movement about the axis of the mandrel with respect to said rod and to the 115 mandrel itself. It is desirable to prevent twisting motions of the rod 25 in its bushing relative to the mandrel and at the same time impart turning movement from said rod to the sleeve 28. For the purpose of accomplishing both of these results the bushing is done longitudinally, as shown at 120 29, and the rod carries a transverse pin or bushing, 30, which works in a spiral groove, 31, in the surrounding sleeve or tube 28, the two 125

slots 29 and 31 being of considerable length and the parts being so organized and combined that when the arm 35 is shifted to the left (as seen in Figs. 7 and 8) the end or pin 30 will ride in the left-hand end of the spiral groove 31 and will turn the sleeve 28 in a direction to unclasp the clamping element 23 to its closed or closed-up position. Any suitable means may be used for permitting the movement of the shiftable member or sleeve 28 to the position of clamping section 23 of the mandrel, this being easily being illustrated at 22 for the purpose of 70 means of these during the assembly of the 75 23 is positively moved in any direction, and the other by connecting thereto a chain 42 throughout the length thereof, and in its normal position the chain 42 is positioned at a considerable distance beyond the right-hand end of the bushing 26, the ends being joined for this purpose being in the position shown in Fig. 1, the coiled spring 32, mounted in the sleeve 28 and engaging at its right-hand end the left-hand end of the rod 25, and at its opposite 25 end the right-hand end of a long rod 41, also carried in said sleeve, which rod 41 is held in its left-hand position by the spring 32. The rod 25 is intended to be forced in against the pressure of the spring 32 and 30 turn the sleeve 28 to swing the clamping element 23 to its clamping position, or the closing up of the usual shiftable or swinging bearing for one end of the mandrel and by the action of such shiftable bearing.

35 The shiftable bearing just referred to is in the present construction carried at the upper end of a swinging arm 35, pivoted at 36, on the bed of the machine near the right-hand end thereof, to swing about said pivot and shift the mandrel-bearing from a mandrel-supporting to a mandrel-releasing position. In this construction the arm 35 also preferably has a sliding movement, and the sliding movement of the arm 35 when 40 the mandrel is to be released takes place in advance of the swinging movement. In order to provide for this sliding movement of the arm 35 the frame member carrying the pivot 36 of the arm is slotted at 37, for a distance sufficient to permit said arm to be moved to the right a distance corresponding approximately to the length of the bearing surface, the object being to permit the bearing at the upper end of the arm 45 35 to be entirely withdrawn from the bushing 26 secured to the mandrel before said arm swings to its lowermost position. This swinging support for the right-hand mandrel-bearing is shown in Figs. 1, 2 and 4, 50 from which it will be seen that the arm is supported at its upper and lower ends for limited sliding movement on two parallel guides, to wit, the walls of slots 37 and the end of bushing 26, and that in addition to 55 this sliding movement the arm also has a 60 swinging movement about the pivot 36 when the arm reaches the right-hand end of the slot 37, at which time it is clear of the bushing 26. The shiftable mandrel-bearing support carried by the arm 35, may be any 65 suitable for the purpose of properly supporting the mentioned journal—the bushing 26 for reception. Here it is illustrated as a 70 eccentric cylindrical bearing member 38, adjustably mounted in the upper end of the 75 arm 35 (see Figs. 7 and 8) and adapted to be held in place by any of its longitudinally adjustible means by suitable cuts, such as 80 V-grooves, on the externally threaded ends of the bearing member. The bearing member is 85 a bushing having at the inner end of the 90 two shoulders of sufficient size to receive the bushing 26, the outer end of which and of the bearing 38, preferably engage one element, 95 for supporting and thrust ball-bearing, the 100 105 110 115 120 125 130 135 140 145 150 155 160 165 170 175 180 185 190 195 200 205 210 215 220 225 230 235 240 245 250 255 260 265 270 275 in its operative or full-line position, shown in Fig. 5, when it reaches the left limit of its swing movement to the left from its center.

The bell crank lever 18 is attached to the elements being described, as a connecting finger, by an fixed eccentric mechanism, so as to swing about the pivot. The eccentric lever 18 operates with a detent 19, as shown in Fig. 5, and serves to engage the clutch 17, so as to start said mechanism in the right-hand position, as described, to release the clutch 17, so as to start lever 15, and permit the clutch 17 to be rotated by the gear-wheel 10. The stop or stop-rod 15 is particularly formed for a purpose, as will be described in connection with the clutch 17, as shown in Fig. 5.

Thus the bell crank lever 18, in its operative or full-line position, is in a position of supporting the mandrel 14, so as to place for supporting the right-hand end of the mandrel, swing the eccentric connecting element 18 of the mechanism so as to bring the lever 15 into a position of supporting the clutch 17, so as to start and operate the clutch, so as to start the rotation of the mandrel, and the operations just described are intended to take place in the order named, viz., the mandrel 14 being first shifted, first to its operative position, then the paper is gripped by the clamp 16, and after the paper is clamped in place the rotation of the mandrel is started.

In winding a sheet of paperboard, paper, or other material around a rotating mandrel to form a tube it is customary to turn the mandrel a number of times corresponding to the thickness of the tube to be formed. In the machine shown, the tube made by the machine is one having six layers, on five of which a suitable adhesive, such as glue-paste, or silicate of soda, is intended to be spread by proper paste-applying means, the mandrel of the present machine being intended to make seven complete revolutions for the formation of each tube, the last revolution being required to complete the rolling down and wiping off of the last, or outside, layer of the tube, as by a collector-roll or other device, as well as to give a sufficient plane for completing the cutting and trimming of the built-up tube.

On the turning of the machine as herein described, and the rotation of the mandrel, the sheet clamped therein is carried around by said mandrel. At a point, point M , the rotation of the mandrel M suitable means will come into action, for applying adhesive to the sheet carried by it. Any suitable paste-applying means may be employed, but, preferably, one having a distributing-roll, shiftable into and out of operative relation with the surface of the mandrel. On the starting of the machine the paste-applying means with its distributing-roll is out of operative relation with said mandrel, but in this case is intended to come into action as

soon as the clutch 17 is engaged, as at and 33, so as to engage the right end of the mandrel, come into the distributing-roll of the machine 30, and into the distributing-roll 30. The paste-applying means 30, shown in detail, is a reservoir 31, having a tube 32 of the body of the machine 30, which is connected to a distributing-roll 33, and a distributing device 34, which includes a tube 35, a distributing roll 36, a distributing device 37, and a tube 38, all of which are supported, in unit, on the right end of a swinging frame 39, which is pivotally mounted on the main frame 40 of the machine. A connecting-rod 41, pivotally mounted on the frame 40, to which these parts are attached, connecting to the main shaft 42 of the machine, and carrying, such as a distributing roll 43, supported, in a well-known manner, in a distributing device 44, so as to bring it into engagement with a distributing roll 45, which is supported, in a well-known manner, in a distributing device 46, which is pivotally mounted on the shaft 45, the distributing roll 45 being its lower end, and the distributing device 46 being the other end of the distributing roll 45, and is carried by the end of the long arm 47 of a lever 48, which is pivotally mounted about a pivot 49. The lever 48, as shown in the drawings, 33, 34, and 35. A spring, shown as 50, serves to hold the lever 48 in a position in the position shown in Fig. 5, just as to say, with the latch member 63 thereof in engage-ment with the latch member 62 on the rock frame of the distributing roll, for the purpose of holding and distributing roll 45, normally out of engagement with the mandrel. In this position the arm 47 is in the path of a cam 60, on one end of the mandrel, and when this cam reaches a point in the free revolution of the mandrel, where it comes adjacent to the latch device, just described, to engage the arm 47, rocks the lever 48, and releases the latch member 63, so that it will engage the distributing roll 45, and the lever 48 is shifted to bring the roll 45 into engagement with the paper 110 being wound on the mandrel. The means herein illustrated for bringing the distributing roll 45 into its operative position is a strong spring 51, carried on a rod, 71, pivotally mounted with the rock-frame of said machine, and winding, by two suitable stops. This construction and operation of these parts will be clearly understood, particularly by reference to Fig. 5, and 33. When released from the latch device, the rock-arm 60 is swung into position for engagement with a cam 72 on a shaft 73 of the rock of the machine in a manner to be hereafter referred to, said rock-arm having a roller, 74, at its extreme end for engagement with the face of the cam.

The shaft 73 is freed from the mandrel 14, by means of spur-gears, 75 and 76, which have a ratio in this instance of seven to one, which corresponds to a six-ply tube, 130.

that is to say, the mandrel M makes seven revolutions while the cam-shaft 73 is making one. The drive for the various rolls of the paste-applying means is not, however, 5 from the source just described, but from a belt-driven pulley, 77, secured to a short shaft 77 journaled at the right-hand end of the machine, the connections from said shaft being through spur-gears, such as 78 and 79, 10 and spur-pinions, 80 and 81, to the distributing-roll and the doctor-roll respectively from the main roll 53, as will be evident from Figs. 2 and 3. The operation of the various devices of the paste-applying 15 means may be controlled by a suitable manual lever, 82, controlling a clutch element, such as 83, for coupling and uncoupling the rolls of the paste-applying means and the driving pulley 77 by which they are operated.

The mandrel and the paste-applying rolls after being started continue to operate until paste has been applied to the desired length of the surface of the sheet being 25 wrapped around the mandrel. In this case after adhesive has been applied to the fourth layer of the sheet, a shiftable device or plunger carried on the rock-frame of the distributing-roll is intended to be brought 30 into position for subsequent engagement by a part that will engage and shift it, to throw said distributing-roll out of action. Here a cam, such as 84, on the cam-shaft 73 co-operates with and rotates a cam, 85, loose 35 on the shaft 55 of the distributing-roll frame and rocks said cam 85. This last named cam co-operates with a plunger, 86, mounted to slide back and forth in a bore in the rock-arm 59, and having at its upper 40 end an anti-friction roller, 87. Normally this plunger is held in, as shown in Fig. 5, by a suitable spring, such as 88. When forced out by the rotation of the cam 85, after the application of adhesive to the 45 fourth layer of the paper has been completed, said plunger will be held in its outermost position, shown in dotted lines in Fig. 5, by the top of the cam 85.

At the end of the application of adhesive 50 to the fifth layer of the tube being formed, the plunger 86 is intended to be engaged by an element movable with the mandrel M, and shifted from the position shown in dotted lines in Fig. 5, to move the distributing-roll 55 and its rock-frame away from said mandrel. The means illustrated herein for this purpose is a cam, 89, which is secured to the mandrel-shaft and rotates therewith. The action of the cam 89 forces the distributing-roll and the rock-frame away from the mandrel in opposition to the spring 70 and to a position where the rock-frame arm 60 will be engaged by the latch device 62 to hold the distributing-roll in 60 its shifted or inoperative position. Follow-

ing the disengagement of the cam 84 with the cam 85 the latter will be returned to its inoperative position shown in Fig. 5 under the action of a spring 61.

After the engagement of the roll 87 by 70 the cam 89 in the manner just described, and the shifting of the distributing-roll away from the surface of the paper on the mandrel, about one and five-eighths revolutions of the mandrel remain to be made to finish the tube being formed. During the last revolution of the mandrel and while the cam 69 thereon is passing the arm 67 of the latch device before described, for latching the distributing-roll and its frame in their 80 inoperative position, said roll and frame are held away from the paper by other suitable means. In the construction shown a cam, 72, on the cam-shaft 73 comes into engagement with the roller 74 on the rock-arm 69 of the 85 rock-frame in which the distributing-roll is mounted, and holds said rock-arm, frame and roll out of action until the parts are in position again for the detent 63 to engage the coacting member 62 and lock the rock-frame out of action until the proper point is reached in a new series of operations.

One of the principal features of the machine is suitable means for not only maintaining the sheet being wound in proper contact with the mandrel, and with successive layers or plies as these are wound on the mandrel by the continued revolution thereof, but for positively laying and smoothing the last portion or layer of the 100 sheet, in order to produce a tube with a perfectly finished surface, having the last ply snugly adhering to the next adjacent one. The finishing of the tube is preferably effected by a wiping action due to the continued rotation of the mandrel while pressure is brought to bear on the surface of the sheet to resist the advance of the last ply of the sheet. This resistance in the machine illustrated is produced by employing a wiping-on device having a movement during this period that is the reverse of the direction of travel of the mandrel. The wiping-on device used may be of any suitable construction for the purpose, but as here shown 115 embodies both a calender-roll, such as 21, and an endless belt, 92, mounted to travel about said calender-roll and around two other rolls, one of which is shown at 93 and is at times a driving roll, and the other of 120 which is illustrated at 94, and is mainly a guide-roll. This wiping device is intended to have a surface movement in unison with the movement of the surface of the mandrel during the major portion of the revolution 125 of the mandrel for the purpose of winding the sheet into a tube. During the last or seventh revolution of said mandrel, however, this movement is intended to be reversed to produce a wiping action on the tube, tend- 130

ing to smooth out the paper and especially to cause the end of the sheet to adhere smoothly and firmly to the preceding layer. The calender-roll 21 is mounted at the upper end of slides, 95, movable diagonally up and down in tubular guides 96, on the main frame-work, and each slide has on one side of it a rack, 97, for engagement with a pinion, by means of which it is moved back and forth in said guide for a purpose to be hereinafter referred to. The rear roll 94 around which the endless belt 92 passes is supported in any suitable manner, it being shown as mounted in the upper end of a rock-frame, 98, adjustable as by means of rods, 99, pivotally connected thereto and adjustable to different substantially horizontal positions. A suitable belt-tightening device is also preferably employed in connection with the endless belt 92, it comprising in this case a roller, 100, bearing against the under side of the lower run of the belt and carried by rock-arms forming part of a rock-frame, 101, pivoted on a rock-shaft, 102, and adjustable in position for the purpose of varying the tension exerted on the belt. The adjustment device shown is similar to that at 99 in that it embodies rods connected to it, but in addition it has coiled springs, 104, working between suitable stops and adjustable for the purpose of applying regulable pressure to the roll 100 and at the same time permitting yielding of the parts.

The main roll 93 around which the endless belt 92 travels is normally free to turn on its shaft 105, and normally the belt, which is in contact with a considerable portion of the circumference of the mandrel, and the calender-roll 21, by which the belt is held against said mandrel, are free to turn in unison with the paper and the mandrel. These parts, however, are intended at the proper time, as before stated, to be driven positively in the reverse direction to that in which the mandrel travels and for the purpose of obtaining such a movement suitable connections are made, preferably to the main driver. Here the shaft 6 which carries the pinion 9 for imparting movement to the spur-gear 10 that drives the mandrel also carries at its inner end a spur-gear, 106, which meshes with a spur-pinion, 107, near the left-hand end of the shaft 105 carrying the roll 93. This pinion 107 is intended to impart movement to the shaft 105 when a suitable clutch, such as 108, is thrown into action. This clutch is intended to be thrown in on the seventh or last revolution of the mandrel, and the coupling operation is controlled by a cam, 109, on the cam-shaft 73, which at the proper point in its rotation strikes an anti-friction roll carried at the upper end of a shifting lever, 110, pivoted at 111 on the bed-plate or main frame of the machine, which shifting lever has a second

upwardly-extending arm, 112, engaging in the usual manner a collar, 113, shiftable on the left-hand end of the shaft 105 into engagement with the clutch 108, for the purpose of starting into rotation the shaft 105 in the same direction as the mandrel, to cause the belt 92 to travel in a direction opposite that of the surface of said mandrel, and thus produce a wiping-on action or pressure on the paper of the last layer, and especially at the end of the sheet.

In the machine shown it is intended that the mandrel shall be stopped at the end of the seventh revolution. Suitable automatic stopping means will be employed for this purpose, that shown in the present machine embodying a cam-wheel, 114, on the cam-shaft 73 near the left-hand end thereof, which cam-wheel co-operates with the starting lever or releasing lever 13 before described, and serves to restore it to its normal position. In the construction shown said lever 13 has a second upwardly-extending arm, which is indicated at 13', terminating in an antifriction-roll which drops into a cam-groove of the cam-wheel 114 when the machine is in readiness to be stopped. This results in the latching of the lever 13 to the spring-pressed detent 17 again, as shown in Fig. 9, and the consequent stopping of the shaft 11. The stopping of the mandrel, however, does not result in the stopping of the travel of the belt and calender-roll in the reverse direction to that in which the mandrel was traveling, and this movement of the endless belt to wipe on and smooth out the last layer of the tube may continue as long as the operator deems necessary.

For the purpose of completing the tube by cutting and trimming the same, the usual cutter mechanism may be employed, which comprises a cutter-bar, adjustably mounted in the standards 5 and 5', and carrying in this instance a plurality of rotary cutters, 115, adapted to be thrown into and out of action by a suitable hand-lever, 116, in a well-known manner.

On the completion of the winding and cutting of the tube, various parts of the mechanism require to be thrown out of action or operated. One element of the mechanism that will be thrown out of action at this time is the calender-roll and other elements of the wiping-on device. The throwing of this part of the machine out of action is accomplished in the present case by the operator raising a handle and crank, shown at 117 and 118, which crank is secured to a shaft, 119, carried by the brackets, 120, and having spur-teeth in mesh with the teeth of the racks 97. When the crank 118 is thrown up by the operator these spur-pinions will be turned and the racks, with the calender-roll and the upper

- run of the belt carried thereby, will be rendered. This movement of the crank 118 is also intended to bring about the disengaging of the roll 35 from the driving spring 5 before described and thereby the disengaging of the endless belt 32. The movement is shown herein for this purpose at a slot 114, secured to the shaft 119, a link, 121, having an anti-friction-roll in contact with said slot 114 and being forked at the upper end to embrace and be guided by the slot 114, as indicated by dotted lines in Fig. 1, and the crank lever, 123, connected with said link 121 and a connecting-rod, 124, connected to the lower end of the shifting lever 116, thus forming a stop, 125, therein adapted to be engaged by the free end of the lever-end of the belt-crank 118. On the turning of the crank 118 and the lowering of the telegraph 29 roll the shaft 119 also operates through the connections just described to release the clutch 108, which results in the disengaging and stopping of the wiping-on mechanism.
- The crank 118 is also connected, as by 25 means of rack-bars, 126, on the shaft 119, to links, 127, connected to levers, 128, carrying the guide-plate 20, before described. This guide-plate is thrown out for the purpose of permitting another sheet to be inserted in place when the crank 118 is thrown up, as just described. The manner in which the guide-plate 20 and its rack frame 128 operate with the sheet to locate it properly will be obvious.
- 35 The last and one of the most important functions preferably performed by the same manual action just referred to, viz., the turning of the crank 118, is the shifting of the movable mandrel bearing to its respective position. This may also be accomplished by very suitable connections or connecting-rod, 129, shown carrying a pivot-bearing-rod, 130, adapted to engage the under side of the rear end of the latch-lever 117 and release it from the swinging frame 35, by raising the upper long end of said latch-lever 117, the unlatching of said frame, moreover, the automatic action will come into operation for shifting the frame 35 to the extreme right-hand end of its movement in a second, time, after which said frame will then again, its pivot 36 in the right-hand end of its slot, and thereby to the position shown in dot-and-dash lines in Fig. 1. The manner illustrated herein (see Fig. 3) for automatically shifting said frame to the right, is a spring-pressed rod, 131, the spring, 132, of which works between a suitable stop on the rod and a cheek of a bracket, 133, in which said rod is guided at one end. At its other end said rod is also suitably guided and carries an anti-friction-roll cooperating with the periphery of an annular member, 134, concentric with the axis of oscillation 36 of
- 35 The action of the sheet. The flow of the swinging frame 35 at the end of its movement to its position of rest is taken up by a suitable holding or cushioning device, such as the coil-spring 135, the function of which may be any 70 device or device for the purpose.
- It will be evident from what has been said to this flag, wherein as the swinging frame 35 will be bearing its grooves away from the annular member 134 it will be forced out by 75 the weight of the plate 35, the sleeve 29 operating in the direction of the reverse of that before described, and the movable clamp 23 thereof will be caused to open up the gap 24, 25, and the fixed jaw 22 and thus 80 be prepared for the reception of another sheet.
- The plates 20 are now thrown out by means of the handle 114 and the completed 85 Skiffle 116 is removed from the mandrel. 85 Skiffle 116 is preferably employed for carrying out the starting, or stopping, of the sheet of paper. This means is shown in the diagram as a suitable member having two large grip-stays, 136, movable in 90 pairs 137, at the left-hand end of the mandrel 116 (see Fig. 3, 4 and 5), the said grip-stays being suitably connecting the sleeve 29 and being connected to a rod, 138, having a handle 139 for shifting the gripper back 95 and forth.
- 100 The action of the device before described is to catch the sheet, a treddle, 140, is firmly engaged to the lower end of the sleeve 29 of the mandrel 116. By means of this the sleeve 29 may be lowered and held to force the sheet 20 to be held up again face upward, and the sleeve 29 may hold this sheet at the top edge, and at release cause the sheet to fall by the descent of all of the 105 members connected to said sleeve 29.
- 110 The sheet, when once held for coating, is caused to pass into the paste-applying device and to catch into action in the manner of action of the pasteur, when 119 a sheet is passed past it around the mandrel and a suitable pressure is exerted with this, as by a treddle or similar suitable blocking device, for protecting the swinging of the sheet, before rod 136 is engaged 115 with the sleeve 29, and applying adhesive thereto, especially when a sheet is so passing through the sleeve. Any suitable means may be employed for preventing the paste-applying device from being thrown into action when a sheet is passing through, and this is obtained by application of the adhesive to the periphery of the mandrel itself. For this purpose there is illustrated at 121 a ring which is stamped to be secured to the periphery of the mandrel (see Fig. 3) that it is within, less than the thickness of one ply from the mandrel surface, in which position it is held by a suitable spring, such as shown at 122, and by a shaft, 123, and a 120

- stop-finger, 134. Said shaft also carries a cam, 145, which cooperates with a hook, 161, on a rock-arm, 162, in fixed relation with the rock-arm carrying the distributing roll. 5 With this finger set in the position described the cam 145 will be under the hooked portion 146 of the arm 162 and will prevent the swinging of the distributing roll into engagement with the template. If, however, a sheet has been properly gripped in place by the mandrel and is passing through the machine properly, the finger 161 will be turned aside, 163, and the cam 145 will be turned from under the hook 162 and will release the sheet from the hold of the distributing roll and the sheet will pass easily over the template. 10 The right hand of the operator will then move the handle of the press, 140, on the center of the mandrel, 100, so as to move the machine, however, the press, 140, is so designed as to be capable of being moved in the direction of the distributing roll and the sheet will move to the right when the handle is moved in conjunction with the right hand of the operator.

What I claim is:

1. In a machine of the class described, the combination with a rotary mandrel, of paste-applying means, means for moving the paste-applying means, means for moving the paste-applying means into operative relation with the tube-winding means, means to normally prevent such movement of the paste-applying means, and means operable upon said last-mentioned means of a point determined point during the operation of the tube-winding means to permit movement of the paste-applying means into operative relation with the tube-winding means.

2. In a machine of the class described, the combination with a rotary mandrel, of paste-applying means, means for moving the paste-applying means, means for moving the paste-applying means into operative relation with the tube-winding means, means to normally prevent such movement of the paste-applying means, and means operable upon said last-mentioned means of a point determined point during the operation of the tube-winding means to permit movement of the paste-applying means into operative relation with the tube-winding means, and means operable during the operation of the tube-winding means to shift the paste-applying means to its inoperative position.

3. In a machine of the class described, the combination with a rotary mandrel, of paste-applying means, means for moving the paste-applying means, means for moving the paste-applying means into operative relation with the mandrel, a lever device for normally holding the paste-applying means by its inoperative position, and means to release said lever device to permit the paste-applying means to move into operative relation with the mandrel.

4. In a machine of the class described, the combination with a rotary mandrel, of paste-applying means, means for moving the paste-applying means into operative relation with the mandrel, a latch device for normally holding the paste-applying means in its inoperative position, and an element rotatable with the tube-winding means to act on said latch device and permit the paste-applying means to move into operative relation with the mandrel.

5. In a machine of the class described, the combination with a rotary mandrel, of paste-applying means, means tending to move the paste-applying means into operative relation with the mandrel, a device for normally holding the paste-applying means in its inoperative position, a rotatable open and latch device to permit the paste-applying means to move to its operative position, and a cam for shifting the paste-applying means back to its inoperative position.

6. In a machine of the class described, the combination with a rotary mandrel, of paste-applying means movable into and out of operative relation with the mandrel, a cam rotatable with the mandrel to effect movement of the paste-applying means to its operative position, and a second cam rotatable with the mandrel to effect movement of the paste-applying means to its inoperative position.

7. In a machine of the class described, the combination with a rotary mandrel, of paste-applying means movable into and out of operative relation with the mandrel, a latch device for holding the paste-applying means in its inoperative position, means rotatable with the mandrel for actuating said latch device to permit the paste-applying means to move to its operative position, and means effective during certain revolutions of the mandrel for preventing the paste-applying means from moving to its operative position during such time as the mandrel is so rotated.

8. In a machine of the class described, the combination with a rotary mandrel, of paste-applying means movable into and out of operative relation with the mandrel, a latch device for holding the paste-applying means in its inoperative position, means rotatable with the mandrel and operable upon said latch device to permit the paste-applying means to move to its operative position, means to shift the paste-applying means back to its inoperative position, and means effective during certain rotations of the mandrel and while the paste-applying means is in its inoperative position for preventing the latter from moving to its operative position when said latch device is operated upon.

9. In a machine of the class described, the combination with a rotary mandrel, of paste-applying means, means effective for bringing the paste-applying means into operative relation with the mandrel, a cam rotatable

- with the mandrel for shifting the paste-applying means to its inoperative position but normally ineffective for so shifting the paste-applying means, and means normally lying out of the path of said cam 5 when the paste-applying means is in its operative position but adapted to be projected into the path of said cam at a predetermined time to permit the cam to shift 10 the paste-applying means to its inoperative position.
10. In a machine of the class specified, the combination with a mandrel and means for rotating the same, of paste-applying means, 15 means for shifting said paste-applying means into action, means associated with the mandrel for controlling said last-named means, and means for maintaining said paste-applying means in action throughout 20 a predetermined plurality of revolutions of said mandrel.
11. In a machine of the class specified, the combination with a mandrel and means for rotating the same, of paste-applying means 25 having a distributing-roll shiftable into and out of operative relation with the mandrel, means for shifting said distributing-roll into action, means associated with the mandrel for controlling said last-named means, and 30 means for maintaining said distributing-roll in action throughout a predetermined plurality of revolutions of said mandrel.
12. In a machine of the class specified, the combination with a mandrel and means for 35 rotating the same, of paste-applying means, means for shifting said paste-applying means into action, an element associated with the mandrel for controlling said last-named means, means for maintaining said 40 paste-applying means in action throughout a predetermined plurality of revolutions of said mandrel, means for putting said paste-applying means out of action, and means for stopping the mandrel after the putting of 45 the paste-applying means out of action.
13. In a machine of the class specified, the combination with a mandrel and means for rotating the same, a paste-applying means having a distributing-roll shiftable into and 50 out of operative relation with the mandrel, means for shifting said distributing-roll into action, an element associated with the mandrel for controlling said last-named means, means for maintaining said distributing-roll 55 in action throughout a predetermined plurality of revolutions of said mandrel, means for shifting said distributing-roll out of action, and means for stopping the mandrel after the distributing-roll has been shifted 60 out of action.
14. In a machine of the class specified, the combination with a mandrel and means for rotating the same, of paste-applying means, means for shifting said paste-applying 65 means into action, an element associated
- with the mandrel for controlling said last-named means, means for maintaining said paste-applying means in action throughout a predetermined plurality of revolutions of said mandrel, means for putting said paste-applying means out of action, and automatic means for effecting the subsequent stopping of the mandrel at the end of a predetermined number of additional revolutions. 70
15. In a machine of the class specified, the combination with a mandrel and means for rotating the same to wind a sheet thereon, of means for wiping on the last end of said sheet as it travels with the mandrel, and means operable during the last part only of 80 the operation of the mandrel to move said last-named means in a direction opposite to the direction of travel of the mandrel. 75
16. In a machine of the class specified, the combination with a mandrel and means for 85 rotating the same to wind a sheet thereon, of means embodying a calender-roll and an endless belt for wiping on the last end of said sheet as it travels with the mandrel, and means operable during the last part 90 only of the operation of the mandrel to move said belt in a direction opposite the direction of travel of the mandrel. 90
17. In a machine of the class specified, the combination with a mandrel and means for 95 rotating the same to wind a sheet thereon, of paste-applying means, means for putting said paste-applying means into and out of action, means for wiping on the last end of said sheet after the paste-applying means 100 has been put out of action, and means to automatically start movement of said last-named means in an opposite direction to the movement of the mandrel when the paste-applying means is put out of action. 105
18. In a machine of the class specified, the combination with a mandrel and means for 110 rotating the same to wind a sheet thereon, of paste-applying means, means for putting said paste-applying means into and out of action, means comprising an element whose surface is movable relative to the surface of the mandrel to effect wiping on of the last end of said sheet, and automatic means for putting said wiping-on means into action on 115 the putting of the paste-applying means out of action.
19. In a machine of the class specified, the combination with a mandrel and means for 120 rotating the same to wind a sheet thereon, of a calender-roll coöperating with the mandrel and movable in unison therewith during the first part of the operation of winding said sheet on the mandrel, and means for reversing the direction of rotation of the calender-roll during the last part of the operation of winding said sheet upon the mandrel. 125
20. In a machine of the class specified, the combination with a mandrel and means for 130 rotating the same to wind a sheet thereon, 140

- of an endless belt movable in unison and in contact with the mandrel during the first part of the operation of winding said sheet on the mandrel, and means for reversing the direction of travel of said belt during the last part of the operation of winding said sheet upon the mandrel. 5
21. In a machine of the class specified, the combination with a mandrel and means for 10 rotating the same to wind a sheet thereon, of a wiping-on device movable in unison and in contact with the mandrel during the first part of the operation of winding said sheet on the mandrel said device embodying a 15 calender-roll and an endless belt mounted to travel around the calender-roll and to engage the mandrel throughout an arc of considerable length, and means for reversing the direction of movement of said calender- 20 roll and endless belt during the last part of the operation of winding said sheet on the mandrel. 25
22. In a machine of the class specified, the combination with a mandrel and means for 30 rotating the same to wind a sheet thereon, of a wiping-on device normally in engagement with the mandrel and having a movement in unison therewith, means for reversing the direction of movement of said wiping-on device, and means for shifting said wiping-on device out of operative relation with the mandrel. 35
23. In a machine of the class specified, the combination with a mandrel and means for 40 rotating the same to wind a sheet thereon, of a wiping-on device normally in engagement with the mandrel and having a movement in unison therewith, and means for automatically reversing the direction of movement of said wiping-on device at the end of a predetermined plurality of revolutions of the mandrel. 45
24. In a machine of the class specified, the combination with a mandrel and means for 50 rotating the same to wind a sheet thereon, of a wiping-on device normally in engagement with the mandrel and having a movement in unison therewith said device embodying a calender-roll, and means for automatically reversing the direction of movement of said wiping-on device at the end of a predetermined plurality of revolutions of the mandrel. 55
25. In a machine of the class specified, the combination with a mandrel and means for 60 rotating the same to wind a sheet thereon, of a wiping-on device normally in engagement with the mandrel and having a movement in unison therewith said device embodying a calender-roll and an endless belt mounted to travel around it, and means for automatically reversing the direction of movement of said wiping-on device at the end of a predetermined plurality of revolutions of the mandrel. 65
26. In a machine of the class specified, the combination with a mandrel and means for 70 rotating the same to wind a sheet thereon, of a wiping-on device normally freely movable in unison and in contact with the mandrel, means for driving said wiping-on device positively in the reverse direction, and means for shifting said wiping-on device out of engagement with said mandrel and disconnecting it from said positive driving means. 75
27. In a machine of the class specified, the combination with a mandrel, and means for 80 rotating the same to wind a sheet thereon, of a wiping-on device comprising an endless belt, means to render said belt ineffective during the first part of the operation of the winding of said sheet on the mandrel, and for rendering said belt effective during the last part of the operation of winding said sheet upon the mandrel. 85
28. In a machine of the class described, the combination with tube-winding means, of paste-applying means, means for shifting said paste-applying means into action at a predetermined time when a sheet is passing through the machine, and blocking means for preventing such shifting of the paste-applying means when no sheet is passing through the machine. 90
29. In a machine of the class described, the combination with a rotary mandrel, of paste-applying means having a distributing-roll movable into and out of engagement with the mandrel, and blocking means co-operative with the mandrel for preventing the shifting of said distributing-roll into action when no sheet is passing through the machine. 95
30. In a machine of the class described, the combination of a rotary mandrel, a sheet clamp associated therewith, a shiftable bearing for one end of the mandrel, a wiping-on device comprising a plurality of rollers and a belt passing over said rollers, means to move one of said rollers bodily toward and away from the mandrel to move a portion of the belt into and out of operative relation with the mandrel, and means whereby the actuation of said last-named means simultaneously actuates said shiftable bearing and said sheet clamp. 100
31. In a tube making machine, the combination with a rotary mandrel, of paste-applying means, means tending to move the paste-applying means into operative relation with the mandrel, a latch device for normally preventing such movement of the paste-applying means, a cam associated with the mandrel to actuate said latch device whereby the paste-applying means is brought into operative relation with the mandrel during the first revolution of the latter, means to shift the paste-applying means out of operative relation with the mandrel after a predetermined number of revolutions of the latter, and means to pre- 115
- 120
- 125
- 130

vent movement of the paste-applying means into operative relation with the mandrel during the next revolution thereof when the latch device is again actuated during such revolution.

Signed at Rochester, in the county of

Monroe, and State of New York, this 24th day of April A. D. 1913.

EDGAR M. HAWKINS.
